DESIGN FOR A GAS DETECTOR

Owen G. Bennett, Wilkinsburg, Pa., assignor to
Catalyst Research Corporation, Pittsburgh,
Pa.

Application January 10, 1942, Serial No. 105,118

Term of patent 14 years

To all whom it may concern:

Be it known that I, Owen G. Bennett, a citizen of the United States and a resident of Wilkinsburg, in the county of Allegheny and State of Pennsylvania, have invented a new, original, and ornamental Design for a Gas Detector, of which the following is a specification, reference being had to the accompanying drawing, forming a part thereof.

Fig. 1 is a front elevational view of a gas detector embodying my new design;

Fig. 2 is a side elevational view thereof;

Fig. 3 is a rear elevational view thereof, a portion of the screen protector feature being broken away for purposes of showing the detector elements;

Fig. 4 is a bottom plan view thereof, portions being broken away for convenience in illustration.

I claim:

The ornamental design for a gas detector, substantially as shown.

OWEN G. BENNETT.
